Thornton & Bates.

UNITED STATES PATENT OFFICE.

LOUIS D. ROUND, OF CLEVELAND, OHIO, ASSIGNOR TO DAVID ROUND AND SON, OF CLEVELAND, OHIO, A PARTNERSHIP.

HOIST.

SPECIFICATION forming part of Letters Patent No. 721,968, dated March 3, 1903.

Application filed October 9, 1902. Serial No. 126,418. (No model.)

To all whom it may concern:

Be it known that I, LOUIS D. ROUND, a citizen of the United States, residing at Cleveland, in the county of Cuyahoga and State of Ohio, have invented a certain new and useful Improvement in Hoists, of which the following is a full, clear, and exact description, reference being had to the accompanying drawings.

10 The invention relates to hoists in general, and particularly to that type wherein the chain-wheel shaft is provided with a worm-wheel and a worm-screw is arranged to rotate said worm-wheel.

15 The object of the invention is to reduce the friction incident to turning the worm-screw, and thereby to enable the hoist to be operated by less power.

20 The invention consists, primarily, in the construction and combination of parts herein-after shown in the drawings and set forth in the specification and claims.

Referring to the drawings, Figure 1 is a side elevation of a hoist similar to what is known as a "Harrington" hoist. Fig. 2 is a vertical section through the gearing. Fig. 3 is a front elevation of the bearing-adjusting ring, and Fig. 4 is a detailed view of the parts associated about said ring.

30 Referring to the parts by letters, A represents the casing in which the operating-worm is rotatively mounted and which incloses the worm-wheel which is keyed to the chain-wheel shaft B, also mounted in said casing.

35 α^3 represents a retaining-plate for holding the worm in place, while in the upper end of the casing is a supporting-hook B', which is pivoted upon a pin b.

40 Upon the end of the shaft B is a chain-wheel D, carrying the hoisting-chain E.

In the inner end of the recess α in the casing the bearing-cup H² is secured, while upon a reduced end portion f⁸ of the worm-shaft F a cone-cap H is fitted. Suitable balls are 45 arranged between it and said cup. A shoulder f² is formed on the worm-shaft for the purpose of serving as an abutment for a cone J', which is fixed upon said shaft. The worm-shaft F passes out of the casing through the 50 plate α^3 . Between this plate and the cone J' is the cup J², between which and the cone J'

is a raceway for balls J. This cup may be adjustably secured to the casing in any suitable manner. Preferably it has an outwardly-extended cone-like end J³, which enters an annular recess k' in an adjusting - ring K. This ring is fitted to the recess in the casing, and it embraces the worm-shaft, along which it may be moved endwise. In the outer face of this ring are three recesses k, more or less, 60 into which the inner ends of the adjusting-screws L project. These screws screw through the plate α^3 and by bearing against said ring properly adjust the pressure on both sets of balls. The rotation of the ring K is prevented by the engagement of the screws in said recesses. It will of course be understood that the cup J² and ring K may be in one piece; but there is this advantage in making them separately—viz., it is easier and less expensive to harden the cup. That is also the reason why the cone H is made independently in the form of a cup fitting the end of the worm-shaft. When several screws are used to adjust the tension on the balls, one may 75 by screwing one in farther than the others put a greater pressure on one side of the axis than the other. If this is done, the cup J², because its cone-shaped end is fitted into a recess in the ring K, will automatically adjust itself so as to equalize the pressure.

Having described my invention, I claim—

1. In a hoist, the combination with a casing containing a recess which is closed at one end, a worm-wheel which is mounted in said casing, a worm coöperating therewith and mounted in said recess, with a ball-bearing cup in the closed end of said recess, a cone on the worm coöperating with the cup to form a ball-raceway, a second cone on said worm near 90 the open end of said recess, a coöperating cup adjustably held in the open end of said recess and coöperating with said cone to form a ball-raceway, and antifriction-balls in said ball-raceways. 95

2. In a hoist, in combination with the casing, of a worm - wheel mounted therein, a worm coöperating with said worm-wheel and having a reduced inner end portion, a cone-cap upon said reduced end portion, a bearing - cup mounted in said casing, balls between said cone-cap and said bearing-cup, a 100

cone secured upon the shaft of said worm, a bearing-cup supported by the casing, balls between said bearing-cup and said cone, and means for adjusting said cup, substantially as specified.

3. In a hoist, in combination with the casing, of a worm-wheel mounted therein, a worm coöperating with said worm-wheel and having a reduced inner end portion, a cone-cap fitted upon said reduced end portion, a bearing-cup mounted in said casing, balls between said cone-cap and said bearing-cup, a second cone secured to the worm-shaft, a ball-bearing cup having a cone-like extension, an adjusting-ring having an annular recess to receive said extension, and means for adjusting said ring, substantially as described.

4. In a hoist, in combination with the cas-

ing, of a worm-wheel mounted therein, a worm coöperating with said worm-wheel and having a reduced inner end portion, a cone-cap upon said reduced end portion, a bearing-cup mounted in said casing, balls between said cone-cap and said bearing-cup, a second cone secured upon the worm-shaft, a bearing-cup having a cone-like extension, an adjusting-ring having an annular recess in its inner face, and a plurality of recesses in its outer face, and screws in the end of the casing for engaging in the last-named recesses, substantially as described.

In testimony whereof I hereunto affix my signature in the presence of two witnesses.

LOUIS D. ROUND.
